(57) **CLAIM**

The ornamental design for a healing and scanning cap, as shown and described.

DESCRIPTION

FIG. 1 is a perspective view of a healing and scanning cap according to the design;

FIG. 2 is a front plan view thereof;

FIG. 3 is a rear view thereof;

FIG. 4 is a top view thereof; and,

FIG. 5 is a bottom view thereof.

The features shown in dashed lines do not make up part of the claimed design.
